UNITED STATES PATENT OFFICE.

SAMUEL G. GOSS, OF GLENCOE, ILLINOIS, ASSIGNOR TO GOSS PRINTING PRESS COMPANY, A CORPORATION OF ILLINOIS.

SHEET-HANDLING MACHINE.

1,311,886.

Specification of Letters Patent.

Patented Aug. 5, 1919.

Application filed October 12, 1915. Serial No. 55,397.

To all whom it may concern:

Be it known that I, SAMUEL G. Goss, a citizen of the United States, and a resident of Glencoe, Illinois, have made Improvements in Sheet-Handling Machines, of which the following is a specification.

The invention relates to machines for handling sheets, and more particularly to machines for cutting sheets from a web running from a printing press, or like machine, and forwarding them to a collecting cylinder or like device, the collected sheets usually being forwarded to a folding mechanism, with or without the intervention of a stitcher. The objects of the invention will in part be set forth hereinafter, and in part will be obvious herefrom.

The invention consists in the novel parts, constructions, arrangements, combinations and improvements herein shown and described.

The accompanying drawings, referred to herein and forming a part hereof, illustrate one embodiment of the invention, and together with the description serve to explain the principles thereof.

Of the drawings:—

Figure 1 is an elevation of a machine constructed in accordance with the principles of the invention;

Fig. 2 is an end elevation looking at Fig. 1 from the right;

Fig. 3 is a view, partly diagrammatic, showing one position of the mechanism and one stage in the cutting and forwarding of the sheets; and

Fig. 4 is a view similar to Fig. 3, but showing the mechanism and material in a different position.

In a large class of high grade magazine or periodical work, and in other high class pamphlet or paper book work as well, the printing is done on a web run through a perfecting rotary press, the fresh printed web being cut into sheets, the sheets being collected, and folded in a single run through the machine, the product of the machine being usually the completed magazine or periodical.

The cutting in this class of work is usually

done by rotary cutters severing successive sheets from the running web, and the cut sheets are collected or superimposed one on the other by means of a collecting cylinder.

A usual form of collecting cylinder has spaces upon its periphery for three sheets in succession thereabout, while the printing or form cylinders of the press have the plates arranged with four pages around the cylinder. During the operation of the machine, consequently, the fourth printed sheet is superimposed on the first sheet on the collecting cylinder, and so on, until a complete set of the printed sheets is built up on one of the sheet spaces upon the collecting cylinder. The same process or procedure, of course, will be in progress, although in different stages, at the other sheet spaces on the collecting cylinder. When a set of sheets is completed upon one of the sheet spaces of the collecting cylinder, it is deflected or stripped off and is forwarded to stitching or folding mechanism, or to both, operating either successively or simultaneously.

The sheets are taken and held upon the collecting cylinder by suitable means, such as grippers, the grippers opening to receive the successive sheets fed or forwarded thereto, and then opening to release the complete set of sheets which go forward through the machine. The periphery of the collecting cylinder is sufficiently large, preferably, to take the sheets arranged thereabout and to provide therebetween space for the gripper mechanism. By such an arrangement there is no interference between the tail of one sheet and the head of the next, nor is there smudging of the tail of the sheets by the moving grippers, as would be the case where the periphery of the collecting cylinder is in integral ratio, or is precisely equal in length to three sheet lengths, in which case the grippers would have to be beneath the tail of a sheet and would have to lift it each time they operated to take a new sheet or to release the sheets.

Where the collecting cylinder periphery is larger than the precise ratio to the sheet length, that is, when proper gripper space

75

80

100

is provided in the periphery of the collecting cylinder between the successive sheet spaces, the collecting cylinder must travel faster, that is, have a greater peripheral speed than the web and web supplying means, in order to bring the heads of the successive sheets to the successive grippers.

It is very desirable and necessary in high class work that the superimposed sheets 10 register exactly or precisely with each other, and by the present invention the cut off sheets are speeded up and delivered to the collecting cylinder at the peripheral speed of that cylinder. The sheets are thus at 15 rest relatively to the grippers when taken thereby, and a simple and exact gripper action is secured, there is no jerking or slipping of the sheets, and they are superimposed in nice and exact register. This is of 20 great importance in securing a neat and uniform superimposing of the sheets at a high speed, one of the prime objects of this class of machines being to secure a very high class of printing at high running speeds.

25 Referring more particularly to the drawings, illustrating by way of example, one embodiment of the invention, a perfected web α from which the sheets are cut is shown at the top of Fig. 1 running in from 30 the printing press or like machine. The web is shown running between rolls 1 and 2, which may be driven pinch rolls or disks, or they may be tape carrying rolls or disks, or other form of web supplying means.

35 The sheets are severed from the running web in a suitable manner, and in the embodied form rotary opposed, coöperating cutters are provided. In said sheet cutting means, a shaft 3 is journaled in the machine 40 frame, said shaft carrying a plurality of circular disks 4 and a web or webs 5 extending longitudinally between the disks. Mounted on the web 5 is a shearing knife 6. In the embodied form, the cutters are double and 45 a second web, or series of webs 7, similar to the web 5 are carried by shaft 1 and disks 4. A shearing blade 8 is mounted on the web 7.

Opposed to, and coöperating with, this 50 mechanism, is a similar mechanism on the opposite side of the web, comprising a shaft 9 mounted in the machine frame and having disks 10 and webs 11 and 12, carrying, respectively, shearing blades 13 and 14. Suitable gearing and coöperating driving means 55 (not shown) are provided for these cutters and the other parts of the machine, and need not be described.

In the embodied form of means for feeding 60 forward the lead or forward end of the running web after a sheet has been cut, and for feeding on the sheet until it is to be speeded up to be taken by the collecting means, there are provided rotary coöperating devices act-

ing on both sides of the web or sheet. A shaft 65 15 is rotatably mounted in the machine frame, and a plurality of circular disks 16 are carried upon the shaft. The disks 16 are interrupted, as shown at 17^a, that is, they have a depressed portion which does not engage the 70 sheet, said devices constituting an embodiment of intermittently or alternately operating sheet gripping and releasing means.

The cooperating mechanism is substantially the same, as embodied, comprising a 75 shaft 18 having a plurality of circular disks 19, the disks having depressed portions 25. When the proud portions of the opposed disks 16 and 19 are passing the path of travel 80 of the sheets, they grip the sheets and feed 80 them forward, but when the low parts 17^a and 25, are passing the sheet pathway, the sheet is released.

For the purpose of guiding and keeping the sheets in their path of travel, guide bars 20 are provided, preferably extending above and between the disks 16 and 18, and downwardly between disks or rolls 31 and 34 and into close proximity to the collecting cylinder. The guides 20 are mounted on a rod 22 supported on the machine frame. On the opposite side of the sheet pathway are like guide bars 21 mounted on a rod 23, carried by the machine frame. The sheets pass along between the two series of bars 20 and 21. 95

In the embodied form of means for speeding up the sheets to the speed of the collecting cylinder, opposed series of coöperating disks are provided, generally similar to the series of disks 16 and 19. In such embodied form, a shaft 30 is mounted in the machine frame. Upon shaft 30 is mounted a series of circular disks 31, having a proud part for engaging and feeding the sheets and a low part 32 for releasing the sheet. 100

The opposed and coöperating mechanism on the other side of the sheet, as embodied, comprises a shaft 33 mounted in the frame of the machine and carrying a series of circular disks 34, having a proud, sheet engaging part and a low part 35. The disks 16 and 19 are running at the speed of the web supply while the disks 31 and 34 are running at the speed of the collecting cylinder. The disks 16 and 19 release the sheet just as it is gripped and begun to be fed forward by the disks 31 and 34. 110

The embodied sheet collecting device is the collecting cylinder 35 already referred to and briefly described. The cylinder 35 is 120 mounted in a shaft 36 journaled in the machine frame. The three sheet carrying spaces upon the periphery of the cylinder are indicated as 40, 41 and 42, and the grippers as 37, 38 and 39. These grippers open and close to take on successively the successively fed and subsequently superimposed sheets which make up the body of the pamphlet. 125

phlet. As previously stated, the periphery of the cylinder 35 is greater than the three sheet lengths by the space required for the three sets of grippers 37, 38 and 39 and the 5 collecting cylinder has a correspondingly greater peripheral speed than the web supply, the sheet cutters and the feeding disks 16 and 19. The grippers are shown somewhat conventionally, but the details of the 10 mechanism are known and will be understood.

Suitable means for receiving the collected sheets are provided, and as embodied, the 15 collected group of sheets is deflected into a tape pathway by a stripper device 43. Bottom tapes 44 are shown running over rolls or disks 45 and top tapes 46 are shown running over rollers or disks 47. The sheet groups or bundles may be conveyed to a folder or a 20 stitcher or both, or forwarded or delivered in some other suitable manner.

The operation of the mechanism will be understood from what has been said, the web α running in from the press, and the 25 double rotary cutters cutting off two sheets for each rotation thereof, as shown in Fig. 3. The disks 16 and 19 feed the sheet onward until it is engaged by the front edge of the proud part of the disks 31 and 34. When so 30 engaged the sheet is released by the low part of disks 16 and 19, as shown in Fig. 4. It is now traveling at the speed of the collecting cylinder and is delivered into the grippers thereon, as the lower sheet is 35 shown in Fig. 3. The front edges of the proud parts of disks 16 and 19 engage the oncoming end of the web, as shown in Fig. 4, and feed it on, the next sheet being cut by the next set of cutters, as shown in Fig. 2, 40 and so on.

It will be understood that a machine has been provided embodying the advantages and features of invention pointed out and explained, as well as other features and 45 advantages which will be understood.

The invention in its broader aspects is not limited to the mechanisms shown and described, but changes may be made therein, within the scope of the accompanying 50 claims without departing from the principles of the invention and without sacrificing its chief advantages.

What I claim as my invention and desire to secure by Letters Patent is:—

55 1. A sheet handling machine for use with printing presses including in combination web supplying means, web cutting means intermittently operating sheet feeding means adjacent to the web cutting means and running at the speed of the web supply, sheet 60 collecting means running faster than the web supply, and means for feeding the sheets to the collecting means at the speed of the collecting means.

2. A sheet handling machine for use with 65 printing presses including in combination web supplying means, web cutting means, sheet feeding means adjacent to the web cutting means and running at the speed of the web supply, sheet collecting means running faster than the web supply, and intermittently operating means for feeding the sheets to the collecting means at the speed of the collecting means.

3. A sheet handling machine for use with 70 printing presses including in combination web supplying means, web cutting means, intermittently operating sheet feeding means adjacent to the web cutting means and running at the speed of the web supply, sheet 75 collecting means running faster than the web supply, and intermittently operating means for feeding the sheets to the collecting means at the speed of the collecting means.

4. A sheet handling machine for use with 80 printing presses including in combination web supplying means, web cutting means, intermittently operating sheet feeding means adjacent to the web cutting means and running at the speed of the web supply, sheet collecting means running faster than the web supply, and means for feeding the sheets to the collecting means at the speed of the collecting means, both said sheet 85 feeding means being located between the sheet cutting means and the sheet collecting means.

5. A sheet handling machine for use with 90 printing presses including in combination web supplying means, web cutting means, sheet feeding means adjacent to the web cutting means and running at the speed of the web supply, sheet collecting means running faster than the web supply, and intermittently operating means for feeding the sheets to the collecting means at the speed of the collecting means, both said sheet 95 feeding means being located between the sheet cutting means and the sheet collecting means.

6. A sheet handling machine for use with 100 printing presses including in combination web supplying means, web cutting means, intermittently operating sheet feeding means adjacent to the web cutting means and running at the speed of the web supply, sheet 105 collecting means running faster than the web supply, and intermittently operating means for feeding the sheets to the collecting means at the speed of the collecting means, both said sheet feeding means being located between the sheet cutting means and the sheet collecting means.

7. A sheet handling machine for use with 110 printing presses including in combination web supplying means, traveling web cutting means, rotary feeding means alternately en-

gaging and disengaging the web and sheet beyond the cutting means and running at the speed of the web, rotary feeding means alternately engaging and disengaging the sheets as they pass therethrough, a collecting device receiving the sheets from said last feeding means, and having the same speed therewith.

8. A sheet handling machine for use with printing presses including in combination web supplying means, traveling web cutting means, rotary feeding means alternately engaging and disengaging the web and sheet beyond the cutting means and running at the speed of the web, rotary feeding means alternately engaging and disengaging the sheets as they pass therethrough, and feeding the sheets when released by said first-mentioned feeding means, a collecting device receiving the sheets from said last feeding means, and having the same speed therewith.

9. A sheet handling machine for use with printing presses including in combination web supplying means, traveling web cutting means, opposed interrupted circular disks feeding the web beyond the cutting means, a collecting cylinder traveling faster than the web supplying means, and opposed interrupted circular disks feeding the sheets to the collecting cylinder at the speed of the collecting cylinder.

10. A sheet handling machine for use with printing presses including in combination web supplying means, traveling web cutting means, opposed interrupted circular disks feeding the web beyond the cutting means, a collecting cylinder having a circumference greater than a precise ratio to the sheet length and traveling faster than the web supplying means, and opposed interrupted circular disks feeding the sheets to the collecting cylinder at the speed of the collecting cylinder.

11. A sheet handling machine for use with printing presses including in combination web supplying means, traveling web cutting means, opposed interrupted circular disks feeding the web beyond the cutting means, a collecting cylinder traveling faster than the web supplying means, and opposed interrupted circular disks feeding the sheets to the collecting cylinder at the speed of the collecting cylinder, said last-mentioned disks engaging the sheets when released by the first-mentioned disk.

12. A sheet handling machine for use with printing presses including in combination web supplying means, rotary cutters cutting the web into sheets, a plurality of disks with interrupted peripheries adjacent to the cutters and running at the speed of the web supply, sheet receiving means running faster than the web supply and a plurality of

disks with interrupted peripheries running at the speed of the receiving means and feeding the sheets thereto.

13. A sheet handling machine including in combination web supplying means, web cutting means, a vertically disposed fixed guideway for the downwardly traveling web end and the sheets cut therefrom and located directly beneath and in operative relation to the web cutting means, a sheet taking cylinder at the foot of the guideway running faster than the web supply, means for acting on the sheets when subject to the action of gravity in the guideway to control their speed and for releasing the sheet taken by the cylinder.

14. A sheet handling machine including in combination web supplying means, web cutting means, a vertically disposed fixed guideway for the downwardly traveling web end and the sheets cut therefrom and located directly beneath and in operative relation to the web cutting means, a sheet taking cylinder at the foot of the guideway running faster than the web supply, means for acting on the sheets when subject to the action of gravity in the guideway to increase their speed to that of the cylinder.

15. A sheet handling machine including in combination web supplying means, web cutting means, a vertically disposed non-traveling guideway for the downwardly traveling web end and the sheets cut therefrom and located directly beneath and in operative relation to the web cutting means, a sheet taking cylinder at the foot of the guideway running faster than the web supply, means acting on the sheets when subject to the action of gravity in the guideway to increase their speed to that of the cylinder and for releasing the sheets to the cylinder.

16. A sheet handling machine including in combination web supplying means, web cutting means, a vertically disposed non-traveling guideway for the downwardly traveling web end and the sheets cut therefrom and located directly beneath and in operative relation to the web cutting means, a sheet taking cylinder at the foot of the guideway running faster than the web supply, means engaging the web end and sheet in the guideway adjacent to and traveling at the speed of the web, means located lower in the guideway than, and engaging the sheet just as and after it is released by, the first-mentioned engaging means.

17. A sheet handling machine including in combination web supplying means, web cutting means, a vertically disposed non-traveling guideway for the downwardly traveling web end and the sheets cut therefrom and located directly beneath and in operative relation to the web cutting means, a sheet taking cylinder at the foot of the

guideway running faster than the web supply, means engaging the web end and sheet in the guideway adjacent to and traveling at the speed of the web, means traveling at the speed of the cylinder and located lower in the guideway than, and engaging the sheet just as and after it is released by, the first-mentioned engaging means.

In testimony whereof, I have signed my name to this specification in the presence 10 of two subscribing witnesses.

SAMUEL G. GOSS.
